(**) Term: **14 Years**

(57) **CLAIM**

(21) Appl. No.: **29/331,684**

The ornamental design for a keying configuration for an electrical connector, as shown and described.

(22) Filed: **Jan. 30, 2009**

DESCRIPTION

(51) LOC (9) Cl. 13-03

(52) U.S. Cl. **D13/154**

FIG. 1 is a perspective view of a keying configuration for an electrical connector showing my new design, the portion in phantom lines in the figures forming no part of the claimed invention;

FIG. 2 is a front view thereof;

FIG. 3 is a side view thereof, the opposite side being a mirror image; and,

FIG. 4 is a top view thereof, the bottom view being identical. The portions of the connector that are not shown form no part of the claimed design.
